[57] CLAIM

The ornamental design for a bottle, as shown and described.

DESCRIPTION

FIG. 1 is a front elevational view of a bottle embodying our new design, the rear elevational view being a mirror image thereof;

FIG. 2 is a view from the left side of the bottle of FIG. 1;

FIG. 3 is a view from the right side of the bottle of FIG. 1;

FIG. 4 is a top plan view thereof; and

FIG. 5 is a bottom plan view thereof.
